UNITED STATES PATENT OFFICE.

ALEXANDER WINTON, OF CLEVELAND, OHIO, ASSIGNOR TO THE WINTON GAS ENGINE AND MANUFACTURING COMPANY, OF CLEVELAND, OHIO.

SPEED-GOVERNOR.

1,082,383.

Specification of Letters Patent. Patented Dec. 23, 1913.

Application filed October 23, 1912. Serial No. 727,414.

To all whom it may concern:

Be it known that I, ALEXANDER WINTON, a citizen of the United States, residing at Cleveland, in the county of Cuyahoga and State of Ohio, have invented certain new and useful Improvements in Speed-Governors, of which the following is a specification, reference being had therein to the accompanying drawings.

10 This invention relates to improvements in speed governors, and is particularly intended for use in connection with explosion engines; though it is capable of use with other types of engines.

15 The object of my invention is to hold a variable speed engine at any desired speed between minimum and maximum by a governor having a constant or unvarying speed.

20 By means of my improved engine governing mechanism, the speed of the engine can be changed at the will of the driver without changing the governing speed of the governor, and the constant or unvariable speed governor will hold the engine at any of its 25 various speeds whether running light or under load.

The accompanying drawing is an end view of a portion of an explosion engine, my improved governing mechanism applied thereto and shown in section.

30 In carrying out my invention any form of governor which acts on the centrifugal principle may be used, and this may be connected up in any desired manner with any 35 desired form of engine throttle without departing from my inventive idea.

The accompanying drawing is intended as one mechanical expression of the inventive idea herein disclosed by which a constant or 40 unvarying speed governor will hold a variable speed engine at any of its speeds between minimum and maximum and whether running light or under load.

45 Referring now to the mechanical expression here disclosed of the inventive idea, 1 is a cylinder of a vertical explosion engine. This cylinder is supplied with an explosive mixture from any desired source (not shown) through a pipe 2, and this pipe is 50 provided with any desired form of throttle (not shown) for controlling the passage of the fluid to the engine and hence the speed or power of the engine; and this is true 55 whether the engine is driven by explosive force, steam or other source of power. So

far as this improvement is concerned, there may be one or more than one throttle for the engine. As here shown, there are two throttle links 3, which may be connected to separate throttles. The lower ends of these links 3 are pivotally connected with the free end 4 of a lever 5, which has its opposite end pivotally connected at 6, to a vertical frame or arm 7. The lower end of this arm 7 is secured to a housing 8, which in turn is supported in any desired manner by the engine frame or casing 9. A shaft 10 passes through the housing 8 and is suitably journaled therein. Suitably journaled in the housing 8 is a beveled gear 11, which gear 70 is driven in any suitable manner (not shown) by the engine, and the gear 11 may be aptly termed, so far as the governing mechanism is concerned, a driving gear. Attached to the shaft 10 is a beveled gear 12, 75 driven by the gear 11, and this gear 12 causes the shaft 10 to revolve. The said shaft 10 extends upward, as shown, and loosely journaled on this shaft is a governor housing 13, carrying the centrifugal governor arms 14. A vertically movable sleeve 15 has its lower end 16 engaging the bell-crank ends 17 of the weighted governor arms, and this sleeve is normally held in engagement with the ends 17 by a spiral spring 80 85 18. The tension of this spring 18 is adjustable by means of an adjusting nut or sleeve 19. A pivotal connection 20 (dotted lines) serves to connect the vertically movable sleeve 15 with the pivot arm 4, so that when the sleeve is moved upward the arm 4 is also moved and the governor links 13 connected with the arm are actuated to close or partially close the throttle for controlling the speed of the engine. 90 95

Connected with or formed as a part of the governor casing 13 is a cone-shaped friction governor driving surface or member 21, which is driven by a friction disk 22. This friction disk 22 is keyed to a revolvable shaft 23 to rotate with the shaft, but is longitudinally movable on the shaft on an elongated key or spline 24. A bevel gear 25 is keyed to the lower end of the shaft 23 and this gear meshes with a gear 26, the latter gear being keyed to and revolved by the shaft 10. Attention is directed to the fact that the shaft 23 is set at an angle parallel with the adjacent side of the cone-shaped surface or member 21, so that as the 100 105 110

friction disk 22 is moved back and forth on the shaft 23, the said disk is at all times in frictional engagement with the cone-shaped surface or member 21. This friction disk 22 is moved back and forth on the shaft 23 at will, by means of an arm 27, which has one end engaging a groove 28 on the hub of the disk 22, while the other end of the arm carries an internally screw-threaded sleeve 29, which receives and is in mesh with a rotatable externally screw-threaded shaft 30. This screw-threaded shaft 30 is parallel with the shaft 23 and carries at one end an operating wheel 31, by means of which the shaft 30 may be rotated by the person controlling the engine:

From the foregoing description it will be seen that the friction disk 22 is driven by the engine and it in turn drives the governor through the intervention of the cone-shaped friction surface or member 21, and the housing 13 which carries the centrifugal governor. It will also be observed that the relative speed of the engine and the governor is controlled by the position of the friction disk on the cone-shaped friction surface 21, that is to say, the friction disk 22 can be moved to a point on the cone-shaped friction surface 21 that has a circumference equal to the circumference of the friction disk 22, and then the friction disk and governor will rotate at the same speed. If the friction disk is moved from this point toward the enlarged end of the cone-shaped surface, the disk 22 will rotate faster than the governor, and when the disk 22 is moved from said point toward the small end of the cone-shaped member, the governor will rotate faster than the disk 22. The result of this variation of the speed of the disk 22, which is driven by the engine and consequently the variation of the speed of the engine in respect to the speed of the governor, is that the governor being set, for instance, to operate the throttle at say 90 revolutions of the governor, for holding the engine at its minimum speed, the movement of the disk 22 toward the enlarged end of the cone-shaped member 21, will require the engine to run faster in order to rotate the governor at its governing speed, whereas if the disk 22 is moved toward the small or reduced end of the cone-shaped member 21, the engine must rotate slower in order to maintain the governor at its set governing

speed. By reason of this fact the operator can increase the speed of the engine while the governing speed of the governor remains constant or unvariable by turning the hand wheel 31 to cause the disk 22 to move to the enlarged end of the cone-shaped member 21, or can decrease the governed speed of the engine by moving the friction disk 22 to the small end of the cone-shaped friction member. By reason of this operation the speed of the engine can be instantly increased or decreased by the operator or engineer without changing the governing speed of the governor, and at the same time the governor will hold the engine at its variable speed from minimum to maximum whether running light or under load.

From the foregoing it will be observed that the governor can be set to begin its governing action at any desired speed of the governor, say from 90 to 350 revolutions per minute, and at the same time the governed speed of the engine can be varied and not change the speed of the governor.

Having thus described my invention, what I claim and desire to secure by Letters Patent is:

1. The combination with a motor, of a governor therefor, a housing for the said governor having its lower portion shaped to form a cone shaped friction member, a driving mechanism between the engine and the governor, the said driving mechanism including a friction variable speed means for the purpose described. 90

2. The combination with a motor, of a governor therefor, a housing for the said governor having its lower portion shaped to form a cone shaped friction member, a driving mechanism between the engine and the governor, the said driving mechanism including a friction speed means, a screw-threaded collar mounted thereon in engagement with the said speed means and an operating lever on one end whereby the said speed means is positively varied for the purpose described. 95

In testimony whereof I hereunto affix my signature in the presence of two witnesses.

ALEXANDER WINTON.
